UNITED STATES PATENT OFFICE

FRANK EDWARD LANGDON, OF BROMLEY, ENGLAND

POSTAL FRANKING MACHINE

Application filed December 26, 1929, Serial No. 416,586, and in Great Britain January 28, 1929.

This invention relates to machines of the kind in which stamps, slogans or other matter either separately or in combination are printed upon envelopes or other articles of mail matter as they are fed through a machine adapted for continuous operation.

The object of the present invention is to provide a number of improvements in machines of the character above indicated but more particularly to provide a machine in which a large variety of values is available and also in which if desired, stamps of each value can be printed in a design different from all the other values which the machine is capable of printing.

According to the invention a machine for printing postal franks or the like is so constructed that the printing element operates in conjunction with a magazine, the whole operating automatically under hand control to select a value or other stamp from the magazine and position it operatively in the printing element.

In order that the invention may be properly understood, reference will now be made to the accompanying drawings which illustrate one form of the invention as applied to a machine in which articles to be printed or stamped are fed over a rotating printing drum and in which:—

Figure 1 is a side elevation of the machine partly in section,

Figures 2 and 3 are sectional end elevations looking in opposite directions,

Figure 4 is a sectional side elevation looking at the opposite side of the machine from that shown in Figure 1,

Figure 5 is a detail view showing the printing drum, magazine and associated parts in side elevation,

Figure 6 is a section on the line 6—6 of Figure 5 and

Figure 7 is an enlarged detail view of part of the driving mechanism for the counter.

The machine shown in the drawings comprises a rotary printing drum 1 enclosed together with co-operating mechanism in a casing 2 and projecting through an opening in a top plate 3 of the casing over which letters or other matter to be stamped are fed

so as to pass between the printing drum 1 and a pressure roller 3a.

The pressure roller 3a is carried by a bell crank lever 4 loaded by a spring 5 which normally presses the roller 3a downwards so as to grip the letters or other matter between the roller 3a and drum 1. A hand lever 6 is provided by which the roller 3a can be lifted against the action of the spring 5 when required to free a letter or other article gripped between the drum 1 and roller 3a for the purpose of removal or adjustment.

The printing drum 1 is fixed on a shaft 7 and is adapted to be rotated for the purpose of feeding a letter or other article through the machine by means of an external crank handle 8 on the shaft 7. The crank handle 8 carries a stop pin 9 adapted normally to abut a fixed lug 10 so as to arrest the handle in the position shown in the drawings, the pin 9 being capable of being withdrawn against the action of a spring by pulling on the handle piece 11 so that it can be disengaged from the lug 10 at will to permit the handle to be turned. A ratchet and pawl 1a disposed within the casing 1 prevents reverse rotation of the printing drum.

Mounted adjacent the printing drum and eccentrically thereto is a cylindrical magazine 12 (Figures 2, 5 and 6) fixed to a rotary shaft 13 which projects through the casing 1 to a handle 13a. The magazine 12 contains a series of interchangeable value stamp or franking dies, one of which is shown at 14 in Figures 5 and 6 and any one of which can be transferred from the magazine 12 to the printing drum 1 and back again by the action of sliding pushers carried on a sliding rod 15 which projects through one side of the casing to an external handle 16.

Each of the value dies 14 is secured to a bevelled plate 17 (see Figures 5 and 6) in such a manner that the plates 17 each with die 14 attached, have sliding engagement with the bevelled edges of a series of radial guide plates 18 and 19 formed in the magazine 12 as shown in Figures 5 and 6. The guide plates 18 extend radially outwards from an inner cylindrical wall 20 of the

magazine 12 whilst the guide plates 19 extend inwardly from an outer cylindrical wall 21 of the magazine 12 and each of the plates 17 with its die 14 attached is supported 5 at its edges only by sliding engagement with the edges of the elements 18 and 19. Although only one plate 17 with die 14 attached is shown in Figure 5 of the drawings, it is to be understood that the magazine carries 10 a series of dies 14 each attached to a plate 17 and supported between the edges of a pair of guide plates 18 and 19.

The magazine 12 can be rotated by the handle 13a to bring any one of the elements 15 14, 17, therein into alignment with a slot 22 in a die holder 23 fixed to the printing drum 1, and the magazine is held releasably in any one of its adjusted positions by the engagement of a spring-pressed roller 24 with 20 one of a series of recesses 25 formed in the edge of a cam disc 26 fixed to the magazine spindle 13. The spindle 13 also carries a disc 27 (see Figures 2, 3, and 4) carrying a series of peripheral number plates 28 one of which 25 is visible through a window 29 in the top plate 3 for the purpose of indicating the position to which the magazine has been adjusted.

The rod 15 carries two pushers 30 and 31 30 which are normally disposed at opposite sides of the printing drum as shown in Figure 2 so as to receive the element 14, 17 in the printing drum between them when the printing drum reaches the position shown in the drawings.

The pusher 30 is formed with a head 32 (Figures 1 and 6) shaped to fit the slot 22 and capable of pushing the element 14, 17 from the printing drum back into its place in 40 the magazine 12 when the rod 15 is moved to the position shown in Figure 6. When the rod 15 is in the position shown in Figure 6 the magazine 12 can be rotated to select a new die 14, and the pusher 31 enables the new die 45 to be transferred from the magazine to the printing drum.

The pusher 31 is in the form of a cylindrical rod which can slide through the magazine 12 and which enters the same through 50 one of a series of holes 33 formed at appropriate positions in the side wall of the magazine 12 as shown in Figure 5. The engagement of the pusher 31 with one of the holes 33 in the wall of the magazine 12 prevents 55 the magazine from being rotated after a value die has been transferred to the printing drum by a movement of the rod 15 to the position shown in Figure 2 and thus maintains the magazine in position to receive the 60 value die back again before being adjusted to select a fresh value die to be transferred to the printing drum.

The pusher 30 is designed to remain in engagement with the groove 22 after a value 65 die has been returned to the magazine by a

movement of the rod 15 to the position shown in Figure 6 and thus prevents rotation of the printing drum whilst a new die is being selected. As can be seen in Figure 2 of the drawings, the pusher 30 becomes disengaged from the slot 22 when a selected die has been transferred from the magazine to the printing drum by movement of the rod 15 to the position shown in Figure 2.

The printing drum shaft 7 is geared by skew gears 34 (Figure 4) to a shaft 35 which is geared through toothed gearing 36 to a squared shaft 37 disposed horizontally in the lower part of the machine and adapted to drive a counter 38 through adjustable gearing hereinafter to be described for the purpose of registering in the counter the total value of stamps impressed.

The adjustable gearing consists of a series of mutilated gear wheels 39 fixed together 85 and mounted to slide on the shaft 37 and to rotate therewith, such mutilated gear wheels being capable of being brought selectively into engagement with two toothed pinions 40 and 41 fixed on parallel shafts 42, 43, one 90 of which drives the units wheel of the counter 38 whilst the other drives the tens wheel thereof.

The cam disc 26 is formed with a spiral cam slot 44 (see Figure 5) which is engaged by a pin 45 on one arm of a bell crank lever 46 whose other arm is formed with a yoke 47 (see Figures 4 and 6) adapted to shift the mutilated gear wheels 39 in accordance with the adjustment of the magazine 12. The mutilated gear wheels 39 are so designed that they will clear the pinions 40 and 41 when the printing drum is in the position shown in the drawings, so as to permit the mutilated gears to be shifted as the magazine 12 is rotated, but when the printing drum is rotated one or both of the pinions 40 and 41 is rotated by selected numbers of the mutilated gear wheels so as to rotate the units and/or tens wheels of the counter 38 to advance the counter through a distance proportional to the stamp impressed.

The mutilated gear wheels are arranged to rotate the sprocket wheels 40 and 41 successively, so that the rotation of the tens wheel, when that occurs, will not interfere with any carrying-over motion which may result from the rotation of the units wheel, and a ratchet drive is interposed in the carrying-over mechanism between the units and tens wheels 115 so that the tens wheel will not be locked when the units wheel happens to be left in such position as to lock the carrying-over mechanism into engagement.

The arrangement of the carrying-over 125 mechanism is illustrated in Figures 4 and 7 of the drawings in which 48 is the units spindle (which may be identical with the spindle 43) and 49 is the tens spindle, which carries a pinion 50 meshing with a pinion 51 on the 130

shaft 42. The carrying-over mechanism consists of a tooth 52 on the units spindle co-operating with a star wheel 53 on the tens spindle. The star wheel 53 is loose on the tens spindle and is arranged to drive the same through a ratchet wheel 54 and ratchet pawl 55, which permits the spindle 42 to drive the spindle 49 when the star wheel 54 is locked by the tooth 52 as shown in Figure 7.

10 Each of the spindles 42, 43, is held against accidental rotation by a star wheel 56 and spring-pressed tappet 57 (see Figure 2).

The printing drum 1 is adapted to make a single rotation for every operation of the machine and operates to feed a letter or other article between the pressure roller 3a and the printing drum and to impress upon such article a value stamp, a cancellation and dating stamp and advertising or other matter. The printing drum is of generally cylindrical form but has a flattened portion 30a which is located beneath the pressure roller 3a when the printing drum is in the position shown in the drawings so as to enable a letter or other article to be introduced between the printing drum and pressure roller and adjusted to a suitable position. The movement of the lever 4 is limited by a stop (not shown) so that the pressure roller does not engage the flattened part 30a of the printing drum but permits a letter or like article to be moved freely between the pressure roller and this part of the printing drum. The top-plate 3 may be provided with a guide 6a for the edge of a letter or with guide lines or any other suitable means to facilitate adjustment of letters or other articles on the plate 3 for the purposes of securing uniformity as to the positions at which the franking stamps and other workings are printed on the letters or other articles.

A cancellation and dating stamp die 58, which may be of any suitable construction, is slidably fitted in the printing drum so that it can be removed laterally through a suitable door (not shown) in the side of the casing for adjustment or for other purposes, and in order to facilitate its withdrawal and replacement it is provided in its bottom face with a dovetail groove flared at its ends and adapted to engage a fixed guide 59 disposed between the side of the printing drum and the side wall of the casing as shown in Figure 3 so as to guide the die into and out of the machine.

55 A die 60 carrying the advertising or other desired matter is similarly mounted on the printing drum and is guided into and out of the machine by means of a guide 61 (Figure 2) similar to the guide 59.

In order to prevent accidental displacement of the several dies in their grooves on the printing drum during rotation of the printing drum, it is preferred to arrange frame plates 2a lying close to the drum on either

side thereof to act as guide plates which prevent the dies from working out of their slideways in the printing drum as the drum rotates. The plate 2a seen in Figure 1 of the drawings is shaped as shown so as to permit of removal of any or all of the dies from the printing drum when the latter is in normal or resting position shown in the drawings.

The machine is provided with inking mechanism comprising an inking roller 62, feed rollers 63, 63a and an ink receptacle 64 having its bottom wall formed with a slot which lies close to the surface of the feed roller 63. The ink receptacle, feed rollers and inking roller are mounted on a frame 65 which is pivoted at 66 to a fixed support and is supported by a spring 67 which has the effect of pressing the inking roller towards the surface of the printing drum so as to enable the inking roller to roll on the dies 14, 58 and 60 as the printing drum rotates. A stop 68 limits the movement of the printing roller so as to prevent it from engaging the surface of the printing drum at points between the dies.

Ink is delivered to the receptacle 64 in measured quantities from a capsule 69 fixed on the top plate 3 and provided in its bottom wall with delivery ports 70 controlled by a spring loaded valve 71 which is adapted to be opened automatically against the action of the spring when a cap 72 having pin and slot engagement with the capsule is applied to close the capsule (see Figure 1). When the cap 72 is removed the capsule 69 can be filled with ink and when the cap is replaced the ink contained in the capsule is delivered through the ports 70 to an inclined chute 73 which delivers the ink to the receptacle 64 (see Figure 3).

The intermediate feed roller 63a is journalled in L-shaped slots 74 in a U-shaped plate 75 which is slidably supported on the frame 65 and controlled by a handle 76 accessible through a door in the casing 1. The feed roller 63a is normally pressed into engagement with the inking roller 62 and feed roller 63 by springs 77 but can be disengaged by sliding the plate 75 so as to bring the spindle of the feed roller 63a into the horizontal parts of the L-shaped slots 74.

In the operation of the machine, assuming that the parts are in the positions shown in Figures 1 to 3 and that the desired value stamp has been selected, when it is desired to stamp a letter or other article, the article is presented between the printing drum and the pressure roller and the printing drum is turned through one revolution by pulling on

the handle piece 11 of the crank handle 8 so as to release the pin 9 and turning the crank handle until the pin 9 again engages the lug 10. This operation will usually feed the letter or other article completely through the ma-

130

chine and so eject it from between the printing drum and the pressure roller, but if the article is of unusual length it may be necessary to raise the pressure roller by means of 5 the lever 6 for the purpose of releasing the article after it has been stamped. When the article to be stamped is of unusual thickness it may be necessary to raise the pressure roller by means of the handle 6 so as to facilitate 10 the introduction of the article between the printing drum and pressure roller.

When it is desired to change the value of the stamp to be impressed the handle 16 is pulled out so as to shift the rod 15 to the 15 position shown in Figure 6 of the drawings thus transferring the value die 14 which was previously in use from the printing drum to the magazine. By this action the printing drum is locked against rotation owing to the 20 engagement of the pusher 30 with the slot 22, and the magazine is freed owing to the disengagement of the pusher 31 from the opening 33 in the magazine. The handle 13a is now rotated so as to adjust the magazine 25 to the appropriate angular position for selecting the desired value die as indicated by the corresponding number plate 28 visible through the window 29 (see Figure 4) whereupon the handle 16 is returned to its original 30 position so as to transfer the selected die from the magazine to the printing drum by shifting rod 15 back to the position shown in Figures 2 and 3. This movement of the rod 15 releases the printing drum owing to the dis- 35 engagement of the pusher 30 from the slot 22 and locks the magazine against rotation owing to the engagement of the pusher 31 with one of the openings 33 in the magazine. The machine is then ready for further use.

40 The rotation of the shaft 13 adjusting the magazine to select a new value die also adjusts the mutilated gear wheels 39 through the action of the cam disc 26 and bell crank lever 46 as hereinbefore described, so that 45 every time the printing drum shaft 7 is rotated to impress a value stamp the counter 38 is advanced by an amount proportional to the value of the stamp impressed.

The machine above described, providing as 50 it does a relatively wide range of values, does not in the ordinary way require a letter or the like to be inserted twice for the repetition of a value stamp or the addition of a second value stamp of different value from the first, 55 but if the circumstances require such repetition the pressure roller can be lifted by the lever 6 so as to facilitate adjustment of the letter for the purpose of impressing the value stamps in the desired positions.

60 The machine above described is not limited in its application to the impression of franking stamps as the die changing arrangement described may equally be applied to the changing of advertising matter, addresses or the like.

I claim:—

1. A machine for printing postal franks on mail matter comprising a rotary printing drum, a pressure roller, means for feeding the mail matter between said drum and pressure roller, a magazine mounted adjacent said printing drum, a series of interchangeable stamp dies slidably carried in said magazine, a casing enclosing said stamp drum and magazine, mechanism having an external actuating handle for adjusting said magazine to bring any selected one of said interchangeable dies into a position to be transferred from the magazine to the printing drum, mechanism having an external operating handle for 70 transferring the selected die from said magazine to said printing drum and for returning the same to said magazine, means for locking said magazine against movement when a die is transferred to the printing drum, and means for locking the printing drum against rotation when said die is returned to the magazine.

2. A machine for printing postal franks on mail matter comprising a rotary printing drum, a pressure roller, means for feeding articles to be franked between said printing drum and pressure roller, a magazine mounted adjacent said printing drum, a series of interchangeable stamp dies carried in said magazine, a casing enclosing said printing drum and magazine, means for adjusting said magazine to bring any selected one of said interchangeable dies into a position to be transferred from the magazine to the printing drum, a sliding pusher for transferring said selected die from the magazine to the printing drum, said pusher having engagement with said magazine for locking said magazine against movement when a die is 90 transferred to the printing drum, a second sliding pusher for returning the die from the printing drum to the magazine, said second pusher having engagement with said printing drum for locking the printing drum 95 against rotation when the die has been returned to the magazine, a sliding carrier for said pushers and an external manipulating handle operatively connected to said sliding carrier.

3. A machine according to claim 1 where- 100 in the magazine comprises a rotary cylindrical body mounted adjacent the printing drum and formed with radial guide plates between which the interchangeable dies are supported 105 by engagement at their edges with the edges of the guide plates.

In testimony whereof I have hereunto set my hand.

FRANK EDWARD LANGDON. 125
